UNITED STATES PATENT OFFICE.

JOSEPH FREDERICK YOUNG, OF MORRISTOWN, NEW JERSEY.

SAFETY PORTABLE SCAFFOLD.

Application filed July 6, 1922. Serial No. 573,127.

To all whom it may concern:

Be it known that I, JOSEPH F. YOUNG, a citizen of the United States of America, and a resident of Morristown, in the county of 5 Morris and State of New Jersey, have invented a new and Improved Safety Portable Scaffold, of which the following is a description.

My invention relates to scaffolds to be used 10 by painters, carpenters, or others doing work requiring the use of a platform arranged to be raised or lowered by degrees and the general object of the invention is to provide a safety scaffold that may be raised or lowered with convenience and in which the platform is arranged to be securely held in the adjusted position.

A further object of my invention is to provide a scaffold improved in various particulars with respect to its portability and the facility with which the scaffold can be assembled or disassembled.

The invention also has in view the production of a light portable structure that 25 can be handled readily by one man if necessary.

The invention contemplates furthermore to make it impossible for the platform to drop except at the will of the person using 30 it and to positively prevent the platform from swaying in any direction.

Reference is to be had to the accompanying drawings forming a part of this specification, it being understood that the drawings are merely illustrative of one example of the invention.

Figure 1 is a side elevation of a scaffold embodying my invention showing the same in position for use;

Figure 2 is a fragmentary side elevation with the raising means for the platform in different position;

Figure 3 is a front elevation of a scaffold;

Figure 4 is a vertical section given to show 45 the raising and lowering assemblage at the inner surface of a side rail;

Figure 5 is a plan view showing the attachment provided at the top of each side rail;

Figure 6 is a sectional plan view as indicated by the line 6—6, Figure 3.

In carrying out my invention in accordance with the illustrated example side rails or supports 10 are provided. A tie bar or 55 girt 11 extends transversely between the side

rails and has vertical slots 12 extending from the lower edge adapted to receive bolts 13 on the side rails, the bolts having wing nuts 13^a. Diagonal braces 14 are provided on the tie bar 11 and secured by bolts 15 and 60 wing nuts 16, the bolts being received in slots 17 in said braces, the arrangement being such that by loosening the wing nuts 13^a, 16, the girt or tie bar may be detached and when the tie is positioned the side rails 10 65 will be held firmly and spaced, adapted to be placed against a wall of a building.

At the upper end each side rail has a clip 18 secured thereto and formed with diverging terminals to contact with the face of a 70 building for holding the scaffold out from the building.

The platform 19 of the scaffold is supported at each end on bars 20, provided at each side rail 10 and disposed transversely to said 75 platform. The platform in practice is preferably made of sheet metal having depending flanges 21 for strength. The platform 19 is formed at its ends with a cut-out portion 22, in which fit the side rails 10. The 80 platform 19 is supported on transverse supporting bars 20 carried by the slides 24. The flanges 21 are continued at the ends of the platform 19 as at 21^a, said flanges 21, 21^a preventing undue displacement of the 85 platform by engaging the bars 20.

Each bar 20 is carried by a slide 24 on the adjacent side rail 10, said slide having a lateral flange 25 beneath each bar 20 and a transverse pin 26 passing through the bar 90 20 and slide 24 completing the connection. The pin 26 secures also the bar 20 and slide 24 to a link 27 the upper end of which is offset obliquely and pivoted as at 28 to an end of a lever 29 fulcrumed on a slide 30 95 corresponding with the slide 24. A U-shaped dog 31 is provided in association with the slide 24, to embrace rail 10 and a similar dog 131 is provided in association with the upper slide 30. The lower dog 31 has a 100 cross bar 32 between the side arms of said dog and a spring 33 is secured at one end of said cross bar 32 and to the link 27 tending to rock the dog into engaging position. The dog 31 (as also dog 131) has a cross 105 bar 34 at the inner side of the side rail 10 and a cross bar 35 above and at the outside of said rail 10 and adapted to engage in any one of a vertical series of notches 36 in the respective side rails 10. The dog 131 has a 110

2
spring 133 secured to its cross bar 32, the lower end of said spring being secured to the fulcrum 38.

It will be observed from Figure 1 that the outer cross bars 35 engage or dog into adjacent recesses 36, thereby sustaining the platform 19 in position. Upon the lever 29 being rocked upwardly the bar 35 of the lower slide 24 will take the resistance and sustain the platform 19 while the movement of the lever about its fulcrum 28 will raise the upper slide 30 and thereby carry the upper dog 131 upwardly for its bar 35 to engage a notch 36 above that notch shown engaged in Figure 1 (see Figure 2). Upon the lever being now rocked in a downward direction the upper bar 35 will take the load and resistance of said lever 29 while the lever will through the link 27 lift the lower slide 24 and with it the platform 19. In this way the rocking of the lever may raise or lower the platform and dog assemblage by a step by step movement.

A guard rail 39 is provided in the form of a rod extending between the levers 29, the ends of the bar being downturned into hook form to engage in eyes 40 in the lever. This rail acts only as a guard for the workmen on the platform and may be removed whenever desired. 23 is a depending flange on platform 19 for strength.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A scaffold including side rails, a platform, slides on the respective side rails and carrying said platform, dogs associated with the slides, said dogs engaging or disengaging the side rails by movements of the slides, means to actuate said slides, said means including a lever adjacent each side rail, and a guard rail detachably held by its ends on the respective levers.

2. A scaffold including side rails each formed with a series of notches at one side thereof, a slide on each side rail, dogs carried by said slides for engaging said notches, additional slides on the side rails below the first slides, a platform carried by the second-mentioned slides, a lever carried by the upper slides on each rail, a connection between each of said levers and the

lower slide on the same rail, and a dog on each slide, said dogs adapted to engage or disengage the rails by a movement of said slides in response to the rocking of said levers.

3. A scaffold including side rails, a slide on each side rail, additional slides on the side rails below the first slides, a platform carried by the second-mentioned slides, a lever carried by the upper slides on each rail, a connection between each of said levers and the lower slide on the same rail, and a dog on each slide, said dogs adapted to engage or disengage the rails by a movement of said slides in response to the rocking of said levers; together with springs secured to the first-mentioned slides and to the adjacent dogs, and additional springs secured to the other dogs and to the connecting means between the levers and the second-mentioned slides, said springs tending to effect engagement between the dogs and the side rails.

4. A scaffold including side rails formed with notches at one side thereof, upper and lower slides on each rail, each provided with dogs engaging said notches, a bar carried by each lower slide, a platform extending between said lower slides supported on said bars, a lever fulcrumed to each upper slide, and a bar pivotally secured to each of said levers and to each of said lower slides, said levers when rocked upwardly raising said upper slides and causing the dogs of said slides to engage the notches immediately above the slides and when rocked downwardly raising the lower slides causing the dogs of such lower slides to engage the notches immediately above said lower slides.

5. A scaffold including side rails, transverse and detachable tie mean for said side rails, said tie means comprising a bar formed with a laterally extending and open slot at each end thereof and an angularly-disposed reinforcing member connected adjacent each end of said bar and each formed at the opposite end with a slot, said slot being open at one end and extending obliquely to the longitudinal axis of said bar, means passing through the slots of said bar and the slots of said reinforcing members for detachably securing said tie means to said side rails, said bar and reinforcing members being detachable as a unit from said side rails, a platform movable up and down said side rails, means slidable on the respective side rails and supporting said platform, and means for clamping said sliding means at various heights on said side rails.

JOSEPH FREDERICK YOUNG.
